UNITED STATES PATENT OFFICE.

BARNES NEVILLE WALLIS, OF WESTMINSTER, LONDON, ENGLAND, ASSIGNOR TO AIRSHIP GUARANTEE COMPANY, LIMITED, OF WESTMINSTER, ENGLAND, A BRITISH COMPANY.

LIGHTER-THAN-AIR CRAFT.

Application filed January 23, 1925, Serial No. 4,161, and in Great Britain January 26, 1924.

This invention relates to lighter-than-air craft.

As is well understood the resultant normal pressure on the inner surface of the gas bag or bags of an airship is greater at the top of the bag than at the bottom, equaling approximately .068 lbs. to the square foot per foot rise in height from zero or approximately zero at the bottom of the bag to the maximum pressure at the top of the bag.

As the gas bags or aerostats are usually adapted to press freely on a flexible network and, as the wires or ropes comprising the network are invariably of uniform pitch throughout both in the high and low pressure areas, each bag tends to take up a so-called elastic curvature or to bulge the network outwards in the high pressure zones of the bag. Consequently, the load is unevenly distributed and unequal strains are set up in the framework, in the case of a rigid ship. Moreover, owing to the unequal distribution of the lifting forces on the framework, undue bending stresses are thereby set up in various parts of the structure. Furthermore, owing to the space taken up by the bulge of the surface of the gas bag or aerostat due to the elastic curvature of the restraining network between consecutive and adjacent structural members, it has not been possible to use gas bags of the largest capacity attainable for a given diameter of airship.

Accordingly, it may be said that the capacity and performance of rigid airships have heretofore been reduced below what may otherwise have been possible owing to the absence of any efficient method of controlling the shape and evenly distributing the lift of the gas bags from their flexible enclosing networks to the framework of the airship.

In the case of non-rigid or semi-rigid airships the shape of the airship is more or less determined by the shape of its aerostats, and owing to the latter taking up the so-called elastic curvature and bulging the network outwards in the high pressure zones the speed and navigability of the airship are reduced.

According to the present invention any desired shape or size of airship, balloon or dirigible may be produced by varying in different sections or zones the pitch of the wires

comprising the flexible network which encloses the aerostat, the wires of each zone or section being also of such a selected pitch that, when subjected to the pressure of the fully inflated aerostat, the network takes up its desired curvature or camber. For example, when it is desired that the network, or each network in the case of airships having a plurality of separate gas bags, when subjected to the pressure of the fully inflated aerostat or aerostats, shall be circular or substantially circular in cross section, the tension of the wires comprising the network is maintained equal and in equilibrium by progressively increasing the pitch of the wires from the high pressure zones at the top of the bag to the low pressure zones at the bottom thereof, thus obtaining what might be termed an "isotonic" or equal tension effect throughout the wires of the enclosing network. In such cases the wires comprising the network will spread out along non-parallel lines or in fanlike formation from a selected minimum distance apart at the top of the gas bag where the pressure is greatest to the maximum distance apart at the bottom of the bag where the theoretical pressure is zero. Any desired system of mesh wiring can be adopted. It is preferred, however, to arrange the wires of the network so that they follow approximately a spiral or helical path around the airship. In the case of a rigid airship having a plurality of polygonal sides or sections each wire of the network enclosing or surrounding a gas bag may have one of its ends connected to a catenary the latter in turn being attached at its ends to a transverse frame, usually at the points where they meet the longitudinal frames. The other end of each mesh wire may be attached to a locating wire disposed parallel to the longitudinal frames said locating wire being attached at its ends to the transverse frames at the points where they meet the longitudinal frames or intermediate. The pitch of the wires in any particular section may, in practice, be determined in advance and locating wires provided each composed, for example, of a length of wire formed with eyelets spaced apart at a distance corresponding to the desired pitch of the wires in any particular

zone, panel or section. The network may, in the first instance, be built up in sections by attaching the wires to the locating wires, the network being then placed in position and attached to the transverse frames.

The same result, i. e. the ability to control the shape of the aerostat at will, may also be attained by varying the tension in each wire in relationship to the angle of inclination of the wire to the longitudinal axis of the ship, the load per foot run of wire being maintained constant, or at any desired figures, throughout all wires by the method previously described. Each wire in development now lies in a straight line, the wires radiating fanwise from the top or upper panel of the aerostat.

A further method in which the isotonic principle is retained is to vary both the load per foot run in contiguous wires and the angle of inclination to the longitudinal axis of the ship in such a manner that the wires will tend to deflect to such a shape that their projection on a right transverse section is the arc of a circle whose radius is equal to the radius of the gas bag.

The aforesaid arrangements may be employed with a reduced number of transversely disposed attachment wires and with or without the catenaries above referred to.

The network may be built up by attaching the wires to eyelets, attachments or other connecting devices, provided on the transverse frames, or on locating wires provided on the transverse frames, the eyelets or attachments for the wires being spaced apart at the required distances.

In order to obtain the isotonic effect and, having found the value of $P \times A = K$, where P is the resultant normal pressure on the inner surface of the top of the gas bag and A the area supported per unit length of wire, the pitch p of the wires in any particular zone or section can be determined by the general formula

$$p = \frac{K}{P^x}$$

where P^x is the resultant normal pressure on the gas bag in the zone where the pitch of the wires is to be determined.

In order that the said invention may be clearly understood and readily carried into effect the same will now be described more fully with reference to the accompanying drawings which show diagrammatically and by way of example a number of different embodiments of the invention, and in which:—

Figure 1 shows a development of half of one of the networks which surrounds a gas bag of a rigid airship, the cross section of the airship to which the network is applied being that of a fourteen-sided polygon 129 feet in diameter and where, therefore, there

is a resultant normal pressure at the top of the bags of approximately 8.2 lbs. per square foot.

Figures 2, 3 and 4 show in development three modified forms of the invention where-in the isotonic principle is retained without the use of a complete series of longitudinal locating wires 2, 2. In these constructions, therefore, only two locating wires 2, 2 are employed these wires being positioned respectively at the top and the bottom of the airship and running parallel to the main longitudinal girders, at these points certain of the wires of the network having one of their ends attached to the locating wires 2, 2 and the other end attached to one of the transverse frames 1, 1, while other wires of the network, have both their ends attached to the contiguous transverse frames 1, 1. The wires 3, 3 which are shown stretching between the frames 1, 1, at Figures 2, 3 and 4 are merely provided to assist in constructing the network in situ as also to prevent the collapse of the network when the gas bags are not fully inflated.

Figure 5 is a sectional end view showing a network constructed on the isotonic principle and located transversely between a pair of contiguous gas bags, and

Figure 6 is a detail view showing the method which may be adopted in pivotally attaching the network shown at Figure 5 directly to the transverse frames 1, 1.

Figure 7 is a longitudinal section showing a gas bag G in place between a pair of transverse networks, H, H.

Fig. 8 is a sectional view showing diagrammatically the position of the passenger cars.

Fig. 9 shows a modified arrangement in which the mesh wires are attached to the transverse frames of the airship by means of catenaries, and wherein intermediate attachment wires are also provided.

In the example shown at Figure 1 each section or panel A, B, C, D, E, F, G of the enclosing flexible network has a length of 63 feet, i. e. the distance between a contiguous pair of transverse frames 1, 1; and a length of side of polygon of 29 feet, i. e. the distance between each pair of locating wires 2, 2. The pitch of the wires in the top section or panel A is approximately 17 inches; in section B, 17.7 inches; in section C, 20 inches; in section D, 24.6 inches; in section E, 33 inches; in section F, 47.7 inches; in section G, 69 inches and in section H, 83.5 inches. The other half of the network on the opposite half of the gas bag will be of similar construction.

The wires where they cross one another are bound together in any suitable manner, for example, by means of rubber tape.

Figures 2, 3 and 4 show the effect of adopting different helix angles in cases where the

load per foot run in contiguous wires as also the angle of inclination of the wires to the longitudinal axis of the ship is varied continuously from the top to the bottom of the bag. In the example shown at Figure 2 the pilot wires 4 and 5 have a helix angle of 72 degrees with reference to the longitudinal axis of the airship; in the example shown at Figure 4 the pilot wires 6 and 7 have a helix angle of 61 degrees, and in the example shown at Figure 5 the pilot wires 8 and 9 have a helix angle of 45 degrees.

Only one half of the mesh wiring has been shown for the sake of clearance but the other half of the mesh is identical with the portion shown. The correct variation of each wire so as to obtain the isotonic effect and cause each wire to deflect to the required arc may be determined by the formula

20

$$p = \frac{K}{P^x}$$

or it may be obtained from the arrangement shown at Figure 1, by positioning each wire at an angle of inclination which is a mean of that any of the wires that extend beyond more than one polygonal section. It may be shown that $\tan \theta$ where θ is the angle of inclination which the pilot wires 4, 5 etc., make with the transverse frames 1, 1. The greater θ the less is the tension of the wires of the mesh wiring and the greater is the lateral pull on the longitudinal wires situated at the top and bottom of the bag. Further, the greater θ the less is the longitudinal component in the longitudinal frames and the less is the side pull on the main transverse frames 1, 1. The wires have equal tension throughout the circumference of any given gas bag thus giving a substantially tangential component at the points of attachment to the structure with no radial component.

Where flexible networks have heretofore been employed the load is usually transmitted to the longitudinal frames as a distributed lateral loading which in turn is transmitted to the transverse frames and thence by suspension wires to the bottom or keel of the airship where the passenger cars, etc., are usually located, whereas the novel construction of network herein described, has the advantage that the reactions obtained at the wire terminals are substantially tangential and, as aforesaid, the load is transferred to the transverse frames as a substantially tangential component, consequently, tangential loading can be resorted to and the passenger cars, etc., may be located at the sides of the airship where the maximum lifts are obtained. Such an arrangement is shown diagrammatically in Fig. 8 wherein the cars M, M' are suspended by cables M', M' from the rigid frame work of the airship. Instead of being connected directly to the

transverse frames 1, 1, the mesh wires may be connected to catenaries 1^a, 1^a; intermediate attachment wires 1^b, 1^b, being also provided.

This location of the main loads, such as 70 the passenger cars, has the advantage that interference with the controllability of the airship (sometimes referred to as fin effect) is avoided, as, when passenger cars are suspended from the keel of the airship, as is 75 usually the case, the tendency of the airship to yaw is increased by the fin-like action of the cars, and, consequently, the size of the vertical fins and rudders has to be increased proportionately to correct this tendency. 80 In cases, therefore, where the passenger cars are slung from the sides of the airship the size of the vertical fins and controlling rudders need not be increased.

As the main loads are attached to or 85 supported from the sides of the airship, in contradistinction to ships of the Zeppelin and other types where the loads are distributed on the underside of the airship, 90 an airship of larger size can be built in a shed of the same size as that required for a much smaller airship of the existing types, as space for the cars at the bottom of the keel does not require to be provided for.

It will be clear that it will not only be 95 possible by the present invention to produce an airship or the like of any desired cross section, but also an airship or the like the shape or configuration of which can be varied at different points along its length 100 so as to obtain the best streamline effects while at the same time preserving the advantage of a flexible enclosing network having so-called isotonic effects.

In all the above cases it has been assumed 105 that the shape to which it is desired to constrain the aerostats or the gas bags is substantially a circular shape. It will be understood however, that the true shape to which each wire must conform is not strictly the 110 arc of a circle, but approximates more closely to the arc of an ellipse.

In cases where a network H is provided and disposed transversely of the airship as 115 shown at Figures 5, 6 and 7 the wires 14, 14 may have no initial tension and may be pivotally attached at their ends (as shown at Figure 7) to the transverse frames 1, 1. On a gas bag becoming deflated, however, 120 the pressure of the contiguous bag G will cause the network to deflect to the arc of a circle (as shown in chain lines at I Figure 7) and not to an elastic curve so that the load per foot run of each wire will be constant and normal and distributed evenly to the framework of the airship.

The transverse frames and the longitudinal frames shown at Figures 5 and 7 may be constructed in the manner described in my co-pending United States application Serial 130

No. 4,504, the transverse frames being constituted by built-up space frame girders which possess great lateral stiffness and in which internal bracing wires can be dispensed with.

What I claim and desire to secure by Letters Patent of the United States is:—

1. An airship, or dirigible comprising an aerostat which is non-circular in any horizontal cross-section and in which the mesh of the network which surrounds the aerostat progressively increases from the high pressure zones at the top of the aerostat to the low pressure zones at the bottom thereof.
  2. An airship or dirigible comprising a plurality of aerostats surrounded by a network, the mesh of which progressively increases from the high pressure zones at the top of the aerostat to the low pressure zones at the bottom thereof.
  3. A rigid airship in which the mesh of the network which surrounds the aerostat progressively increases from the high pressure zones at the top of the aerostat to the low pressure zones at the bottom thereof, each wire of the network stretching between and having its ends attached to a contiguous pair of transverse frames.
  4. An airship or dirigible comprising an aerostat which is non-circular in any horizontal cross-section, and in which the pitch of the wires comprising the flexible network surrounding the aerostat is varied in different zones.
  5. An airship or dirigible comprising a plurality of aerostats each surrounded by a flexible network and wherein the pitch of the wires comprising the flexible network surrounding each aerostat is varied in different zones.
  6. An airship, balloon or dirigible in which the tension in the wires of the network which encloses the aerostat is varied in relationship to the angle of inclination of the wires to the longitudinal axis of the ship, and in which the load per foot run of each wire is maintained constant or at any desired figure by progressively increasing the pitch of the wires from the high pressure zones at the top of the aerostat to the low pressure zones at the bottom thereof.
  7. An airship, balloon or dirigible in which the tension of the wires comprising the enclosing network for the aerostat is maintained equal by varying both the load per foot run in contiguous wires and the angle of inclination of the wires to the longitudinal axis of the ship so that each wire tends to deflect to the desired arc.
  8. An airship, balloon or dirigible, in which the pitch of the wires of the mesh wiring which surrounds the aerostat is progressively increased from the high pressure zones at the top of the aerostat to the low pressure zones at the bottom thereof, each wire being located at such a selected pitch that the load per foot run is constant and normal so that the wires under
- wire being located at such a selected pitch that the load per foot run is constant and normal so that the wires under the pressure of the fully inflated aerostat deflect approximately to such a shape that their projection 70 on a right transverse section is the arc of a circle whose radius is equal to the radius of the aerostat.
9. An airship as claimed in claim 1 in which the main loads such as the passenger 75 cars, are located at the sides of the airship where the maximum lifts are obtained.
10. A rigid airship provided with transverse frames and with a network the wires of which stretch transversely across and are 80 connected at their ends to said frames so as to provide a network between a contiguous pair of gas bags, the mesh of said network progressively increasing from the top to the bottom of the airships.
11. An airship in which the mesh of the network which surrounds the aerostat progressively increases from the high pressure zones at the top of the aerostat to the low pressure zones at the bottom thereof, each 90 mesh of the network being formed by four members which are inclined relatively to the transverse frames of the airship, each member stretching between and being connected at each of its ends to a contiguous pair of transverse frames.
12. An airship as claimed in claim 11 in which intermediate longitudinally disposed attachment members are also provided.
13. An airship, balloon or dirigible in 100 which the pitch of the wires comprising the flexible network or networks surrounding the aerostat or aerostats is varied in different zones or sections, in such manner that when subjected to the pressure of the fully inflated aerostat or aerostats the network or each network takes up the desired curvature or camber and in which the wires are attached intermediately of their length to a longitudinally disposed member or members.
14. An airship, balloon or dirigible of any desired shape in which the tension of the wires comprising the enclosing network or networks for the aerostat or aerostats is maintained equal by varying both the load 110 per foot run in contiguous wires and the angle of inclination of the wires to the longitudinal axis of the ship so that each wire tends to deflect to the desired arc, the wires being attached intermediately of their length to a longitudinally disposed member or members.
15. An airship, balloon or dirigible, in which the pitch of the wires of the mesh wiring is progressively increased from the high pressure zones at the top of the aerostat to the low pressure zones at the bottom thereof, each wire being located at such a selected pitch that the load per foot run is constant and normal so that the wires under

the pressure of the fully inflated aerostat deflect approximately to such a shape that their projection on a right transverse section is the arc of a circle whose radius is 5 equal to the radius of the gas bag, the wires being attached intermediately of their ends to a longitudinally disposed member or members.

16. An airship, balloon or dirigible in 10 which the wires comprising the network which encloses the aerostat are of such a selected pitch that the tension thereof is maintained equal or at any desired figure or in which the network spreads out along 15 non-parallel lines or in fan-like formation from a selected minimum distance apart at the top of the gas bags where the pressure is greatest to the maximum distance apart at the bottom of the bag where the theoretical 20 pressure is zero, the wires being attached intermediately of their length to a longitudinally disposed member.

17. An airship in which the load is transferred to the transverse frames in the case 25 of a rigid airship, or to the fabric which encloses the aerostat in the case of a non-rigid or semi-rigid airship, as a tangential component, by progressively increasing the pitch of the wires from the high pressure 30 zones at the top of each aerostat or gas bag to the low pressure zones at the bottom thereof, the wires being attached intermediately of their length to a longitudinally disposed member or members or to a longitudinally disposed locating strip or strips. 35

18. An airship in which the mesh of the networks which enclose the gas bags progressively increases from the high pressure zones at the top of the bags to the low 40 pressure zones at the bottom thereof and in which the reactions obtained at the wire ter-

minals are substantially tangential, the wires being attached intermediately of their length to longitudinally disposed members.

19. An enveloping network for the gas 45 bags of rigid airships in which the pitch of the wires progressively increases from the top to the bottom of each gas bag and in which each wire is attached intermediately of its ends to a locating member disposed 50 parallel to the longitudinal frames.

20. An enveloping network for the gas bags of rigid airships as claimed in claim 19 in which the ends of the locating members 55 are attached to the transverse frames at the points where they meet the longitudinal frames.

21. An enveloping network for the gas bags of a rigid airship in which the pitch 60 of the wires continuously increases from the top to the bottom of the bag and in which two locating wires are provided located respectively at the top and bottom of the airship, the wires of the network at these points being attached intermediately of their length 65 to said locating wires.

22. An airship in which the mesh of the network which surrounds the aerostat progressively increases from the high pressure zones at the top of the aerostat to the low 70 pressure zones at the bottom thereof, each mesh of the network being formed by four members which are inclined relatively to the transverse frames of the airship, each member stretching between and being connected 75 at each of its ends to a contiguous pair of transverse frames through the intermediary of catenaries.

23. An airship as claimed in claim 22 in which intermediate longitudinally disposed 80 attachment members are also provided.

BARNES NEVILLE WALLIS.
